UNITED STATES PATENT OFFICE.

THOMAS PATTEN, JR., AND CHRISTIAN ANDERSON, OF APPLETON, WIS.

PUMP.

SPECIFICATION forming part of Letters Patent No. 349,951, dated September 28, 1886.

Application filed January 30, 1886. Serial No. 190,282. (No model.)

To all whom it may concern:

Be it known that we, THOMAS PATTEN, Jr., and CHRISTIAN ANDERSON, citizens of the United States, residing at Appleton, in the county of Outagamie and State of Wisconsin, have invented a new and useful Improvement in Pumps, of which the following is a specification.

Our invention relates to that class of pumps which are designed for use in paper-mills for pumping the liquid pulp from one receptacle to another, and are termed "stuff-pumps," but may be advantageously used for a variety of purposes.

The object of our improvement is to produce a greater and more even flow of the liquid or "stuff," and thereby produce paper of even thickness and uniform weight throughout the entire "batch" or quantity desired; also, to produce a pump that is durable in use, its wear being uniform in the valve and seat, whereby it is kept tight and free from leakage; and, furthermore, of such construction as will permit access to its parts for the purpose of removing obstructions and for making the needed repairs. We attain these objects in the manner shown in the accompanying drawings, in which—

Figure 1 is a vertical elevation, partly in section, of the pump upon the line *x x* of Fig. 3. Fig. 2 is a vertical elevation of the pump-cylinder and valve-chambers; and Fig. 3 is a top view upon the line *z z* of Fig. 2, showing the valve *d* in its chamber, the valve-guides *e*, the hand-hole plate *h*, and the clamp *i* by which it is secured in its position.

Similar letters refer to similar parts in the several views.

A is a post of wood, to which the pump is secured by bolts.

B is the pump-cylinder. *C* is its piston.

D D' are the valve-chambers. *d d'* are globe-valves. *E* is the piston-rod, and *F* the connection-rod, by which the piston is given a reciprocating motion by a crank or other suitable device.

a a are feet cast with the pump, by which it is secured to the post *A* with bolts, as shown.

In the upper end of the cylinder *B* is a

gland, *b*, for the retention of packing around the piston, in the usual manner.

Within the valve-chambers are guides *c* and *c'*, by which the valves *d* and *d'* are guided in their vertical movement, and made to fall squarely into their seat and make an immediate and perfect joint. These guides *c* and *c'* are cast with the valve-chambers, ample room being left between said guides for the free passage of both the valves and the liquid it is desired to elevate.

e is the suction-pipe, and *f* the discharge-pipe.

h h' are hand-hole plates, which are secured in place upon the valve-chambers by the clamp and bolts *i i'*, the removal of the plates giving access to the valve and its chamber for repairs thereto, and for the removal of obstructions which may find lodgment therein.

The cylinder *B*, valve-chamber *D'*, supply and discharge pipes, &c., are formed in separate pieces, and screwed or bolted together, both for their easy construction and repairs.

Its operation is not unlike that of pumps which have been long in use. The raising of the piston exhausts the air from the chamber, the valve *d* is raised, and the pulp or liquid enters. Upon the return of the piston the valve *d* is closed, the valve *d'* opened, and the liquid forced up and delivered through the pipe *f* to the place required. The valve-chambers are located in close proximity one to the other, unlike those formerly used for this purpose in paper-mills, whereby the smallest amount of liquid is accumulated under the valve *d'*, and subjected to the suction of the piston on its upward stroke, thereby producing the smallest variation in the amount of liquid elevated at the several reciprocations of the piston.

Having thus described our invention, what we claim, and desire to secure by Letters Patent, is—

1. In a force-pump, the combination of the cylinder *B*, the valve-chambers *D* and *D'*, the plunger or piston *C*, the globe-valves *d* and *d'*, their seats, and the valve-guides *c* and *c'*, the latter formed integral with the chambers *D* and *D'*, respectively, substantially as shown and described.

2. In a force-pump, the combination of a

cylinder, a plunger or piston adapted to be reciprocated therein, two valve-chambers in close proximity one to the other, having each a globe-valve, guides therefor integral with 5 said chambers for guiding the vertical movement of said valves, seats therefor, and the removable cover and hand-holes for giving

access to said valve-chambers, substantially as set forth.

THOMAS PATTEN, JR.
CHRISTIAN ANDERSON.
